(73) **Primary Examiner** — Rashida Johnson(74) **Attorney, Agent, or Firm** — Faegre Baker Daniels LLP(57) **CLAIM**

The ornamental design for a compression undergarment, as shown and described.

DESCRIPTION

FIG. 1 is a perspective view of a compression undergarment. FIG. 2 is a front view of a compression undergarment. FIG. 3 is a back view of a compression undergarment. FIG. 4 is a first side view of a compression undergarment, the second opposing side being a mirror image thereof; and, FIG. 5 is a top view of a compression undergarment. The broken lines in the Figures do not form a part of the claimed design.

1 Claim, 5 Drawing Sheets(56)
